FASTENER ATTACHING MACHINE

Siegbert Wittenberg, Berlin-Halensee, German

Application June 2, 1934, Serial No. 728,800
In Germany October 9, 1933

3 Claims. (Cl. 153—1)

The present invention relates to a machine for the application of fastener members to ribbons and the like and particularly to machines of this kind in which separable fastener members may be fastened continuously with great accuracy in series of adjustable length in a continuous operation and with a large output per hour.

According to the invention the machine is equipped with a device which is adapted to be continuously moved and is formed with grooves or slots adapted to receive separable fastener members and arranged in spaced relation at a distance from each other corresponding to the distance from each other at which the separable fastener members are to be fixed to the ribbons or the like forming the closure. When this device is continuously operated the separable fastener members are deposited at the proper distance from each other on the seams of the ribbons which are fed into the machine at a velocity corresponding to that of the said slotted device and a cooperating device pinches the deposited separable fastener members to the ribbons by pressing together the shanks of such members. The invention also provides mechanical means for interrupting at any desired moment the supply of fastener members to the continuously moving slotted device and the machine may therefore be used for producing closures of any desired length.

Some constructional forms of the invention are shown by way of examples in the accompanying drawings.

Fig. 1 is a side view, partly in section, of a machine embodying the invention.

Fig. 2 is an end view, partly in section, of the same machine.

Fig. 3 is a side view of the control gearing of this machine.

Fig. 4 shows the same gearing in plan view.

Figs. 5 and 6 show details of the guide devices for the ribbons and the separable fastener members.

Figs. 7 and 8 show on a larger scale, in plan view and in side view respectively, how the ribbons are fed through the machine and the fastener members are fixed to the ridge of the ribbons.

Fig. 9 is a vertical sectional view showing another constructional form of the invention at which the slotted device for distributing the fastener members and the cooperating pinching or clamping device form a unitary structure.

Fig. 10 shows still another constructional form of the invention at which also the slotted device for distributing the fastener members and the

cooperating pinching or clamping device form a unitary structure.

In Figs. 1 and 2, 1 denotes a wheel which is formed with slots or recesses *a* adapted to receive separable fastener members 15 and arranged in spaced relation at a distance from each other corresponding to the distance from each other at which the separable fastener members are to be fixed to the ribbons or the like. The wheel 1 is rotated about a horizontal shaft 2, for instance by means of a bevel wheel gearing 3, 4. The fastener members are supplied to the wheel 1 through a feed device 5 a frame element 5a of which is secured with its lower end to the upper portion of the machine frame which supports the shaft 2. (Figs. 2 and 3.) Each time one of the radial slots *a* in the wheel 1 passes the lower open end of the device 5 a fastener member is dropped into the slot with the shanks pointing upwards.

In order to prevent the fastener members from dropping out of the slots when the wheel is rotated in the direction of the arrow a segment-shaped device 7 is provided which is adjustably arranged in a support 8 on the machine frame 9. The device 7 is formed with a knife-edge 6 which projects into the space between the legs or shanks of the open fastener members and holds the same in the correct position. In the support 8 also a band guide 10 is slidably arranged, which guide is formed with a slot 11 (Fig. 6). The ribbon 13 is moved through this slot and hereby the ridge 12 of the ribbon will take up a position above the upper surface of the slot 11 (Fig. 2). The front part 14 of the guide member 10 is downwardly directed and curved in accordance with the periphery of the wheel 1 with which it cooperates (Figs. 1 and 8), and the ridge 12 of the ribbon 13 is moved in a direction tangentially to the periphery of the wheel 1, so that the fastener members 15 dropping from the slots *a* of the wheel 1 are deposited one after the other with the legs spread open on the seam 12 of the ribbon (Fig. 8).

Below the wheel 1, on both sides of the same, two toothed wheels 16 and 16' are arranged (Figs. 1 and 2), which are driven at the same peripheral speed as the slotted wheel 1. The wheels 16 and 16' rotate uniformly on vertical shafts 16'' and are fixed in such a manner to the latter that the shortest distance between the opposing rims 50 of the wheels in the plane of rotation of the same is substantially like the thickness of the ribbon or tape 13 passing between them. The said wheels 16 and 16' feed the tape with a velocity corresponding exactly to the velocity of rotation 55

of the slotted wheel 1. The lower faces of the teeth may be somewhat flattened or chamfered off, in order to prevent the ribbon 13 being damaged by the teeth.

5 The spaces between the teeth of the wheels 16 and 16' are of such a depth, that the distance between the bottoms of adjacent teeth spaces in the plane of rotation of the wheels is exactly equal to the distance between the fastener members 15, which are pinched to the ribbon. Therefore, as indicated in Fig. 7, the fastener members 15, which by the wheel 1 are deposited on the ridge 12 of the tape 13 with their shanks spread apart, are caught in the spaces between the teeth 15 of the wheels 16, 16', and are held and conveyed by the same at a mutual distance equal to the pitch of the tooth spaces. As the peripheries of the wheels 16, 16' now approach each other the shanks of the fastener members are gradually forced together, whereby said members are clamped to the ridge 12 in the manner indicated in Fig. 7.

25 Thus, the uniformly rotating toothed wheels 16 and 16', the pitch of which is equal to the distance between the fastener members 15, feed the tape and also the fastener members and in addition hereto also clamp the fastener members to the ridge 12 of the tape 13. This takes place at a velocity which corresponds exactly 30 to the velocity of rotation of the slotted wheel 1 which distributes the fastener members.

35 In order that the number of fastener members and the length of the closures may be regulated at will and also in order that the fastener members if desired may be arranged in groups with intermediate free spaces, the feed device 5 is at its lower end facing the wheel 1 equipped with a 40 slideable pin 17 or the like by means of which the feed device may be opened and closed. The pin 17 is by a spring 17' pressed out of the feed device 5 whereby the feed channel is opened. The effect of the said spring is counteracted by a 45 pendulum lever 19, which is arranged on a pivot 18 and tends to force the pin 17 into the feed opening of the device 5 whereby the latter is closed. Normally the lever 19 by virtue of its own 50 gravity takes up a position in which the pin 17 is withdrawn from the feed channel. However, as soon as the edge or abutment 20 of a slide 21 strikes against a cam 22 on the pendulum lever 19 the latter is turned on its pivot 18, whereby the pin or locking member 17 is forced into the device 5 and the supply of fastener members is interrupted.

55 The length of the supply periods and also the length of the periods during which the supply of fastening members is interrupted are therefore dependent on the length of the stroke of the slide 21.

60 The slide 21 may for instance be reciprocated by means of the crank mechanism 23, 24 shown in Fig. 3. The stroke of the slide 21 and the lever 24 is adjusted by means of the sliding member 25, which is connected to the lever 24 by means of a pin 25' which projects into a slot 24' in the said lever. The member 25 can be shifted along the slide 21 and be fixed in any desired position on the same.

65 In the form of the invention shown in Fig. 9 a slotted or recessed wheel 26 is fixed to a shaft 27. In the slots or recesses 28 of this wheel the fastener members are located with their shanks spread apart and projecting over the periphery of the wheel 26. When this wheel is rotated and the tape is fed forward at the same velocity below

70 the wheel the fastener members are deposited and fastened to the tape at a distance from each other which is equal to the pitch of the slots.

75 On both sides of the slotted wheel 26 two discs 29 and 30 are arranged the flanges 29' and 30' of 5 which project over the edge of the wheel 26. The said discs are arranged on ball bearings 31 and 32 which are coupled to the hub 26' of the slotted wheel 26 for rotation with the same. The ball races of the said bearings may for instance be of 10 spherical shape in order to allow some lateral deflection of the discs.

80 At the lowermost part of the wheel 26, on both sides of the same, two rollers 33 and 34 are arranged on vertical shafts (not shown), which 15 are fixed in the central bores 33' and 34' respectively in the said discs. The distance between these rollers is so dimensioned, that the lower sections of the discs 29 and 30 are moved somewhat towards each other when the discs pass between 20 the rollers, whereby the discs are deflected about their ball bearings and the upper sections are deflected outwards so that the distance between the same is increased. Due to the inward deflection of the lower parts of the discs 29' and 30' 25 the same will come into contact with the fastener members deposited on the tape and bend the legs of these members together whereby the same are clamped to the ridge of the tape. The fastener members are therefore deposited and fastened in a single working process by the same device, namely the slotted wheel, and this wheel and also the tape for receiving the fastener members are hereby moved continuously.

30 The form of the invention shown in Fig. 10 35 differs from that shown in Fig. 9 in that instead of the flanged deflectable discs located on the shaft of the slotted wheel, jamming or clamping members of quite another form are used. For 40 each slot in the slotted wheel 35 a pair of clamping members 36, 37 is provided the beak-like parts 36', 37' of which project into corresponding 45 grooves 35', 35'' in the lateral faces of the wheel 35. The clamping members 36, 37 are secured in this position by discs 38, 39, which 50 surround the slotted wheel 35, to which they are coupled for rotation with the same.

55 On the lower side of the wheel 35, which is equipped with clamping or pinching members 36, 37 for each groove, two discs 40', 41' are located, 60 which are rotatably arranged on shafts (not shown), which are fixed in the central bores 40 and 41 respectively in the said discs. The lower sides of these discs are formed with flanges 40'', 41'' adapted to act directly upon the clamping 65 members 36, 37 and to force the same inwards, whereby the projections 36'', 37'' of the latter will be pressed against the shanks of the fastener members and fold the same together, so that the fastener members are clamped to the 70 ridge of the tape.

75 It will be obvious that various changes may be made in the details of construction and method of operation herein shown and described without departing from the scope and spirit of the 80 invention as defined by the appended claims.

I claim:

1. In a machine for continuous application of formed separable fastener members to ribbons, tapes and the like, in combination, a recessed 70 distributor wheel for the fastener members adapted for continuous rotation with uniform speed and having radial recesses arranged at a distance from each other corresponding to the distance between the fastener members when the 75

- same are distributed on a tape or the like and fixed to the same, a device for feeding the formed fastener members by their own gravity into said recesses, and a toothed disc on each side of the 5 slotted wheel below the same, said discs being arranged in such a mutual relation, that the shortest distance between opposing outer peripheral faces of the teeth of the two discs, in the plane of rotation of same, is substantially equal 10 to the thickness of the tape passing between them, whereas the shortest distance between opposing bottoms of the spaces between the teeth of the discs is substantially equal to the thickness of a clamped separable fastener member.
- 15 2. A machine, according to claim 1, comprising means for holding the fastener members in the recessed distributor wheel, said means comprising a segment-shaped body adjustably arranged adjacent the periphery of the slotted wheel, and a 20 knife-edge body located on said segment-shaped body, said knife-edge body projecting with its edge into the open space between the spread-apart legs of the fastener members carried by said recessed distributor wheel.
- 25 3. A machine according to claim 1, comprising guide means for a tape to be equipped with fastener members, said means comprising a slot into which the tape may be introduced with the ridge of the tape lying above the outer surface of said 30 slot, the front end of said guide projecting downward between the toothed discs arranged on both sides of the recessed distributor wheel, below the same, and being curved in accordance with the curvature of the recessed distributor wheel.
- 35 4. A machine according to claim 1, wherein the segment-shaped body for holding the fastener members in the recessed distributor wheel and the band guide are adjustably and detachably arranged in a support on the machine frame.
- 40 5. A machine according to claim 1, comprising a supply device through which the fastener members are supplied to the recessed distributor wheel with the shanks pointing upward, a locking member arranged at the outlet end of said supply device adjacent the recessed distributor wheel, spring means for holding the locking member in inoperative position and other means periodically actuated by the driving mechanism of the machine for moving said locking member into locking position.
6. In a machine for continuous application of separable fastener members to ribbons, tapes and the like, in combination, a slotted wheel adapted for continuous rotation and having radial slots arranged at a distance from each other corresponding to the distance between the fastener members when the same are deposited on a tape or the like and fixed to the same, spreadable cheek members partly projecting over the periphery of said slotted wheel, and pressure devices arranged at the lower part of said slotted wheel and being adapted to actuate said cheek members and thereby clamp the fastener members to the tape.
- 10 7. A machine according to claim 6, comprising two flanged discs arranged on both sides of the slotted wheel and coupled to this wheel for rotation with the same, said discs being deflectably arranged in their bearings and projecting with their rims between the pressure devices and the cheek members, said discs being adapted to be deflected towards each other with their lower parts, thereby causing the clamping of the fastener members.
- 15 8. A machine according to claim 6, comprising a pair of deflectable clamping cheek members for each slot in the slotted wheel, said cheek members resting with hook-shaped parts in grooves in the lateral faces of the slotted wheel and at the lower side of this wheel projecting between the pressure devices, the clamping of the fastener members being caused when cooperating cheek members are moved towards each other.

SIEGBERT WITTENBERG.
